SURF-RIDING BOAT

Henri Fournillier, 86 Ave. Victor Dalbiez,
Perpignan, France

Filed Apr. 16, 1958, Ser. No. 50,487

Term of patent 14 years

(Cl. D71—1)

Fig. 1 is a top perspective view of a surf-riding boat showing my new design;

Fig. 2 is a side elevational view thereof;

Fig. 3 is a top plan view of the surf-riding boat; and

Figs. 4 and 5 are front and rear elevational views, respectively, thereof.

I claim:

The ornamental design for a surf-riding boat, as shown.
